UNITED STATES PATENT OFFICE.

ISAAC HAMBLETON VENN, OF YONKERS, NEW YORK, ASSIGNOR TO OTIS ELEVATOR COMPANY, OF EAST ORANGE, NEW JERSEY, A CORPORATION OF NEW JERSEY.

TRAVELING STAIRWAY.

SPECIFICATION forming part of Letters Patent No. 727,720, dated May 12, 1903.

Application filed August 21, 1901. Serial No. 72,791. (No model.)

To all whom it may concern:

Be it known that I, ISAAC HAMBLETON VENN, a citizen of the United States, residing at Yonkers, in the county of Westchester and 5 State of New York, have invented certain new and useful Improvements in Traveling Stairways, of which the following is a specification.

My invention relates to that class of traveling stairways in which a series of steps are connected together so as to travel upon horizontal or inclined planes; and my invention consists in so constructing and connecting the steps that they may be carried in straight or 15 curved lines, either horizontally or upon an incline, and at all times preserving the contact of each tread with the adjacent riser, as fully set forth hereinafter and as illustrated in the accompanying drawings, in which—

20 Figure 1 is an end elevation showing two connected steps of the chain of steps of a traveling stairway; Fig. 2, a plan view of Fig. 1; Fig. 3, an end view showing a series of four steps, one elevated; Fig. 4, a plan of Fig. 25 3; Fig. 5, an inverted plan view of Fig. 1; Fig. 6, a diagram indicating the relations of the treads in a partially-horizontal curve and partially-inclined straight course in the construction shown in Figs. 1 to 5; Fig. 7, a 30 perspective view illustrating the construction where the treads of the steps are of uniform width; Fig. 8, an inverted plan of two of the steps shown in Fig. 7; Fig. 9, a perspective diagram indicating the course which the steps 35 can take in the construction shown in Figs. 7 and 8.

Each step A has opposite side pieces 1, 1, a tread 2, and a riser 3, and in some instances there may be a second riser 4 at the opposite 40 side, the additional riser being required if the steps must ascend upon an incline and thereafter descend upon another incline. The central lines α of the treads must be parallel when the series of steps travel upon an incline, but must diverge when the steps are 45 on a horizontal support, and it is therefore necessary that the steps in passing from a position with the treads flush with each other to one with the treads in different planes 50 shall have a swinging motion, their outer ends swinging to a greater extent than their inner

ends in a circle whose diameter is that of the circle to which the curved portion of the track conforms. To secure this result, I make use of flexible connections between the steps, 55 which connections at the outer ends of the steps are capable of greater movement than those at the inner ends. Preferably these connections are linked connections, and as the steps must rise and fall in respect to each 60 other and also be carried from parallel to radial positions the links must have double joints. As shown in Figs. 2 and 5, where the treads of the steps are widest at the outer ends, the outer connection B consists 65 of two links 7, 8, connected by a universal joint, the link 7 swinging on the stud 9, which may be the axis of the flanged wheel 10, while the link 8 swings on a stud 12, which may be part of a shaft 13, upon which is the 70 intermediate wheel 14. The connection D at the inner ends of the steps consists of two links 15, 16, longer than the links 7, 8, jointed at their inner ends, the link 15, swinging on the stud 19, constituting the axle of the inner flanged wheel 18 of one step, while the 75 link 16 extends to the stud constituting the axle of the inner wheel 18 of the other step. As a result when either step is raised above the other the outer end of the elevated step 80 is carried inward, so that when it reaches its elevated position the widest outer end of the tread overhangs the outer end of the tread below to a greater extent than the inner end. In order to insure the bearing of the edge of 85 each tread against the face of the adjacent riser under these movements of the steps, I make each riser with an outward curve, which curve increases from one end to the other, but extends inward to a greater extent at one 90 end than at the other, as shown.

The proportions and connections of the linkage or flexible connections and the curvature of the risers will depend somewhat upon the formation of the treads. If, as in Figs. 7 95 and 8, the treads are of equal width throughout, then the risers 3 will swell outward beyond the forward lines of the steps at the outer ends and will swing inward to the greatest extent at the inner ends instead of 100 at the outer ends, as when the treads increase in width outwardly. In the latter case also

the axes *w v* of the shafts or studs carrying the outer and the inner intermediate wheels are at an angle to each other instead of parallel, as in the construction shown in Figs.

5 1 to 6.

I do not here claim the particular construction shown in Figs. 7 and 8, but illustrate the same in order to show the application of my invention in its broad sense in connection 10 with steps having treads of different shapes.

The supporting-wheels may be differently arranged, the intermediate wheels 14, however, being upon axes which do not coincide with those of the outer wheels, so as to afford 15 separated bearings upon the outer rails E E and inner rail F, which prevent the steps from tilting, preserving the treads in horizontal position, and preferably the treads and risers extend beyond the end pieces 11, so that the

20 links and end wheels may be below the treads, the outer rails also therefore being below the treads. For increased stability I prefer to connect the side pieces by connecting rods 20 near their lower ends. It will be evident that

25 the side pieces may be differently shaped and that the supporting wheels and links may be arranged in different positions from those shown.

In Fig. 6 I have shown the course which 30 steps having treads of gradually-increasing width may take in which the steps travel in a curved or circular course at *x x'* when the treads are in the same plane and upon a straight but inclined course at *y y'* when the 35 treads are one above the other. In the construction shown in Figs. 7 and 8 the steps can take either a curved course or an incline when the treads are one above the other; but when the treads are flush with each other the 40 steps travel in a straight course in any desired direction, the two structures being thus adapted to different conditions, but in either case the adaptability being secured by flexible or link connections of different characters 45 at different ends of the steps and by providing the steps with risers curved to different degrees in extending from one end to the other to thereby maintain the edges of the treads constantly in contact with the faces of 50 the risers in all positions.

I have not attempted to illustrate the means for imparting movement to the chain of steps, as any of the well-known means heretofore devised for such purposes may be employed.

55 Without limiting myself to the precise construction and arrangement of parts shown, I claim—

1. A traveling stairway having a series of steps and with risers curved to a greater extent at one end than the other, substantially as set forth.

2. A traveling stairway having a series of steps and with risers curved to a greater extent at one end than the other, with link connections between the steps permitting the 65 steps to be shifted from a level to an incline and from parallel to radial positions while preserving at all times the contact of each tread with the riser of the adjacent step, substantially as set forth. 70

3. The combination of a series of link-connected steps each having a riser curved and extending inward to a greater degree at the lower edge of one end than at the other, substantially as set forth. 75

4. The combination of a series of link-connected steps each having at each side a riser curved and extending inward to a greater degree at the lower edge of one end than at the other, substantially as set forth. 80

5. The combination of a series of link steps each having a riser curved and extending inward to a greater degree at the lower edge of one end than at the other with double-jointed link connections, substantially as set forth. 85

6. The combination of a series of link-connected steps each having a riser curved and extending inward to a greater degree at the lower edge at one end than at the other and with side and intermediate supporting- 90 wheels, substantially as set forth.

7. The combination in a traveling stairway of a series of flexibly-connected steps each with a tread widening toward the outer end, and with a curved riser extending inward to 95 a greater extent at the outer than at the inner end, substantially as set forth.

8. The combination in a traveling stairway, of a series of steps with risers curved as set forth, and link connections greater in length 100 at one end than at the other, substantially as set forth.

9. The combination in a traveling stairway, of a series of steps with risers curved as set forth, and double-jointed link connections 105 greater in length at one end than at the other, substantially as set forth.

10. A traveling stairway provided with supporting-rails with level, inclined and curved portions, and flexibly-connected steps having 110 wheels adapted to the rails, and each with a riser curved to a greater extent at one end than the other to preserve contact with the adjacent tread at all times, substantially as set forth. 115

In testimony whereof I have signed my name to this specification in the presence of two subscribing witnesses.
